LISTING ADDING MACHINE

Loring Pickering Crosman, South Orange, N. J.,
assignor to Monroe Calculating Machine Company, Orange, N. J., a corporation of Delaware

Application December 20, 1941, Serial No. 423,810

1 Claim. (Cl. 235—60)

The invention has relation to listing adding machines equipped with suitable platens, tabulating means, and means for automatically controlling the functioning of the machine in accordance with the tabulated position of the platen.

The invention consists in the novel construction and combination of parts, as set forth in the appended claims.

In the accompanying drawings, illustrating the invention,

Fig. 1 is a rear elevation of a machine embodying the invention and showing the tabulating means and associated parts.

Fig. 2 is a detail section through the yieldable connections between the platen and the index tube.

Fig. 3 is a rear elevation of the machine, with parts broken away and numerous parts removed.

Fig. 4 is a left side elevation of the sign controlling mechanism and associated parts.

Fig. 5 is a left side elevation of the accumulator adjusting mechanism and associated parts.

Fig. 6 is a detail left side elevation of the alignment feeler, with the related index element shown in cross section.

In these drawings the invention is shown as applied to a tabulating and program indexing mechanism constructed in accordance with the disclosure of United States Patent No. 2,229,553, issued January 21, 1941, to Loring P. Crosman.

During a registering operation of the machine a trigger 184 (Fig. 1) is engaged above a tabulator detent 7 and moved downwardly, disengaging detent 7 from the shoulder 193 of a notched tabulator bar 1, mounted in the framing 3 of the platen carriage.

The platen carriage, being thus freed from the restraint of detent 7, near the end of the registering cycle of the machine, will be shifted by means of a tape 9, connected with a spring drum 8, until the detent is engaged by the wall or shoulder 193 of the next adjacent notch of bar 1. This engagement serves not only to arrest the platen carriage in its next tabulated position, but also effects engagement of the clutch whereby the accumulator sign control or program mechanism is operated. This is effected as follows:

Detent 7 is pivotally mounted upon an intermediately fulcrumed lever 20 which is normally held by the platen carriage in the full line position illustrated in Fig. 1. Upon release of detent 7, the detent spring 22 will rock lever 20 into the

dotted line position, moving a pin 23 of said lever idly past a click pawl 25 (Fig. 3).

Reengagement of detent 7 with the tabulator bar will cause lever 20, under the pull of the spring drum, to move back to the full line position of Fig. 1, bringing pin 23 against pawl 25 and thereby rocking a latch 21, on which said pawl is mounted, out of engagement with a spring operated lever 36, fulcrumed at 34 on the framing.

Upon operation, lever 36 will engage a pin fixed in a clutch control lever 38, moving the latter about fulcrum 40, out of engagement with the pawl of a spring-engaged, one-cycle clutch 24, of well known design.

Clutch 24 is adapted to connect the motor 48 with a shaft 56, having fast thereon a crank arm 58 (Figs. 3 and 4), connected by link 67 with a rocker 69, mounted on shaft 70. Rocker 69 has spring connections 94 with a series of levers 93, connected each by a link 96 with one end of an intermediately fulcrumed lever 86. The other ends of the levers 86 are connected with feelers 83, having reduced free end portions designed to allow the feelers three positions of adjustment toward the axis of an index tube 82, mounted in the platen carriage, in accordance with the location of a large perforation of said tube, a small perforation or no perforation, in the path of movement of the feeler.

Movement of rocker 69, transmitted from drive shaft 56, will, through springs 94 and suitable guide connections between the rocker and the levers 93, first move these levers forwardly and the feelers 83 rearwardly until the feelers are stopped in one of three positions by index tube 82. Continued movement of rocker 69 will now lift the levers 93 about their connections with the links 96 as a fulcrum, bringing a lug 98 of each lever into contact alternatively with a cam plate 73; into neutral position between the plates, or into contact with a cam plate 74, according to the positioning of the related feeler 83 by the index tube 82. Normally, the cam ends of plates 73, 74 are held in operated position by spring means but contact of the lever 93 with either plate will swing it toward the other plate, bringing the outer cam edge of the displaced plate into the path of return movement of a roller 71, mounted on the rocker 69.

Cam plates 73, 74 extend between lugs 113, 115 of a gear segment 165, so that the segment will be held in its median position, or will be rocked in one or the other direction, by the action of roller 71 on the cam plates, in accordance with

the indexing of tube 82 in the given position of the platen carriage.

The segments 105 engage each with a pinion 133 mounted on a shaft having universal joint connection with the shaft 134 (Fig. 5) supporting an accumulator 76.

Each accumulator shaft 134 has fast thereon one or more cams 122, adapted each when the shaft is held by segment 105 in a displaced position to cooperate with a related cam formed upon a rocker 419, which is reciprocated once during each registering cycle of the machine. When a cam 122 lies in the path of movement of a cam portion of rocker 419, the related accumulator will be moved radially of the reciprocatory differential actuator segments 610, and held with the accumulator gears in mesh with said segments during the forward or during the return stroke thereof. This will effect subtraction or addition in the accumulator, as the case may be, a non-add operation being provided for by rotating the cams 122 into position in which they will not engage the cams of rocker 419.

Mounting of the index tube

In accordance with the present invention the index tube 82 is mounted in the framing 3 of the platen carriage in a manner allowing for longitudinal yielding movement between the carriage and the tube. The ends of the tube engage guiding perforations of the end plates 3 of the carriage, the walls of these perforations providing slide bearings for the tube. Within one end of tube 82 is fitted a thimble 504 (Fig. 1) having a spring plunger 505 which may engage any one of a series of perforations of the tube, and the thimble is further provided with a bolt extension 506, upon which is mounted a sleeve 507 (see also Fig. 2) having a squared outer surface, and held firmly against the thimble by means of a nut and washer 508. Plates 509 have squared perforations engaging the sleeve 507 and are also provided with perforations engaging the stems of a pair of posts 510, secured in the framing 3 of the carriage. Springs 511, surrounding the posts 510, serve to hold the plates 509 separated, one of said plates taking a bearing against the washer 508 and the other plate against the end of thimble 504 and also against the framing, by means of suitable washers.

Sleeve 507 will be held with sufficient firmness against thimble 504 to prevent accidental rotary movement of index tube 82, so that the perforations of the tube will be held in alignment with the feelers 83. Also, longitudinal yielding movement is provided for between the platen carriage and the tube, for a purpose to be described hereinafter. There are several longitudinal series of perforations in index tube 82, providing each a separate and distinct program of operation for the machine, and one end of the tube is shown as knurled so that the tube may be rotated, against the frictional resistance of pin 505, in changing the program, the pin setting in a new hole to provide for angular alignment of the tube to correctly locate the new series of index perforations.

Location of the index tube

It is important that the index tube 82 be accurately located before the feelers 83 are moved

towards the axis thereof, for which purpose means are provided as disclosed in United States Patent No. 2,229,553, hereinbefore referred to.

This means comprises auxiliary index perforations 500 (Figs. 1 and 6) provided in the tube 82, and an auxiliary feeler 501 is pivoted in the framing of the machine at 502. A forward arm of this feeler has a perforation engaged by one arm of an intermediately fulcrumed lever 503, the opposite arm of which engages a slot formed in lever 36 (Fig. 3).

Therefore, whenever latch 27 is tripped by the location of the platen carriage in a new position, lever 36, under the influence of its spring, will rock feeler 501 toward the axis of tube 82. In case of mislocation of the platen carriage, however, feeler 501 will travel only a short distance and will be arrested on the periphery of tube 82.

According to United States Patent No. 2,229,553, the auxiliary feeler provided for accurate location of the platen carriage and index tube relatively to the feelers 83, before these feelers are moved toward the axis of the tube, thus preventing distortion of the feelers by lateral stresses and preventing incorrect setting of the sign control mechanism by misalignment of the index perforations with the feelers. In the present invention the auxiliary feeler also functions to locate the index tube promptly, while the platen carriage, owing to the yieldable connections with the tube, is allowed to vibrate after encountering the tabulator stop.

Since it is no longer important that the carriage be promptly located in a tabulated position, means are provided for absorbing the momentum of the carriage and for bringing it to rest by a harmonic retardation, as follows:

Lever 20 is formed with a cam face 512 (Fig. 1) engaged with an arm of a plate 513, pivotally mounted upon the framing of the machine and normally held by a strong spring 514 in engagement with a fixed stop 515. Upon engagement of detent 7 by a shoulder 193 of bar 1, the plate 513 will allow for movement of the carriage beyond its tabulated position, the cam face 512 of lever 20 being designed to increase the effectiveness of spring 514 as plate 513 is displaced, so that the momentum of the platen carriage will be absorbed by a harmonic retardation, after which the carriage will be returned to the correct tabulated position by means of spring 514. It will be observed that the harmonic retardation is effected by the engagement of cam face 512 with plate 513 at a point progressively further away from the fulcrum of lever 20 and progressively nearer to the pivot point of plate 513.

I claim:

In a listing adding machine having a shiftable platen carriage, tabulating means for said carriage, and means settable to control the functioning of the machine in each tabulated position of the carriage, including an index device movable with the carriage and feelers operable to sense said device; the combination with means for locating the tabulated index device relatively to the feelers; of yieldable connections between the carriage and the index device, and guide supports for the device designed to allow longitudinal displacement thereof relative to the carriage.

LORING PICKERING CROSMAN.
